UNITED STATES PATENT OFFICE.

FREDERICK E. KINSMILLER, OF BRAINERD, MINNESOTA.

CONCRETE-BLOCK MACHINE.

Application filed June 10, 1921. Serial No. 476,603.

To all whom it may concern:

Be it known that I, FREDERICK E. KINSMILLER, a citizen of the United States, residing at Brainerd, in the county of Crow Wing and State of Minnesota, have invented a new and useful Improvement in Concrete-Block Machines, of which the following is a specification.

My invention relates to concrete block machines and has for its principal object to provide a machine adapted to form a block with a continuous air space extending completely through the same.

Another object of the invention is to provide means whereby the side walls and core of the block will be easily withdrawn and removed to permit the block to rest upon the pallet board intact without rotating or otherwise disturbing the position of the portions of the block after the same have been cast.

Another object of the invention is to provide the core of the machine with a central portion adapted to be raised vertically from the block and with end portions adapted to be swung outwardly with the sides or the end walls of the mold so as to leave the block free from the cores upon the pallet board.

A still further object is to pivot the side walls of the mold below the lowermost portions thereof so that when said walls swing outwardly the same do not cause the edges or corners of the block to adhere thereto and so deface the surface of the block.

Another object of the invention is to provide means for holding the anchors employed within the block in proper position, said means being yieldable to permit the removal of the core members of the machine without disturbing the position of said anchor after the block has been cast.

Another object is to provide means for adjustably supporting the pallet within the mold proper.

A still further object is to provide a number of sockets positioned along the periphery of the mold walls which are adapted to receive and hold division plates capable of being positioned within the mold to separate the same into smaller sections whereby smaller sized blocks may be formed.

A still further object is to provide lock-

ing means for the mold walls whereby two side walls and an end wall may be simultaneously locked from movement in an outward direction.

The full objects and advantages of my invention will appear in connection with the detailed description thereof and are particularly pointed out in the claims.

In the drawings, illustrating the application of my invention in one form:

Fig. 1 is a side elevational view of my improved invention with the mold box closed and the parts positioned ready to receive the concrete ingredients.

Fig. 2 is a front elevational view of the machine shown in Figure 1.

Fig. 3 is view similar to Figure 1 of a portion of the device shown therein with the mold walls swung away from the block and the central core member partially removed from the same.

Fig. 4 is a view similar to Figure 2 with two of the mold walls swung outwardly and with the central core member partially raised to show the manner of removal of the same in relation to the block anchors.

Fig. 5 is a plan view of the machine with parts arranged as shown in Figure 1 and with a block positioned within the same.

Fig. 6 is a sectional view taken on line 6—6 of Figure 5.

Fig. 7 is an enlarged detail view of a portion of the anchor holding device shown in Figure 6.

Fig. 8 is an elevational view of one of the locking bars indicated in Figure 1.

Fig. 9 is a plan view of the locking bar shown in Figure 8.

Fig. 10 is a plan view of my improved block machine showing a corner block being formed within the same.

Fig. 11 is a view similar to Figure 10 showing the device for forming a chimney block.

Fig. 12 is an elevational view of one of the division members used in connection with my concrete block machine.

Fig. 13 is a plan view of the machine showing the division member in Figure 12 positioned within the same.

Fig. 14 is a sectional fragmentary view taken on line 14—14 of Figure 13.

tudinal division member similar to that shown in Figure 12.

Fig. 16 is a plan view similar to Figure 13 showing the application of the division member indicated in Figure 15 positioned within the same.

My invention is arranged to construct concrete blocks which have a complete air space extending longitudinally through the block so that the block is divided into two separate portions, a front face and a rear face which are connected together by means of a number of steel anchors securely embedded in the two sections. I have found that with this type of block a very high degree of insulation is secured so that buildings constructed therewith are constantly maintained dry and heat is prevented to a large extent from passing through the said walls thereby causing the buildings to be cool in summer and to hold their heat in winter.

My invention, which is best shown in Figure 1, comprises a frame A on which is supported a pallet board B surrounded by a removable mold C. To the rear of mold C is positioned a table D which is carried from the support A which table is so arranged as to hold all of the tools and other devices used in the construction of my improved blocks. These various parts will now be described in detail.

The frame A which is shown in detail in Figures 1, 2, and 3 comprises two standards 20 and 21 which are formed with legs 22 and 23 connected together to form a head portion 24. The two standards 20 and 21 are connected together at their head portions 24 by means of a table 25 which extends throughout the length of the machine and which is bolted thereto by means of bolts 26. Beneath the table 25 and parallel to the same is provided a longitudinal brace 27 which is bolted to a pair of outwardly extending flanges 28 on the standards 20 and 21 by means of bolts 29. The brace 27 is provided with a pair of upwardly extending brackets 30 best seen in Figure 2, which have a flange 31 by means of which the same may be bolted to the head portion 24 of the said standards 20 and 21 by means of bolts 32. With the table 25 extending completely across the standards 20 and 21 and rigidly bolted thereto and with the additional brace 27 and its brackets 30 the whole device may be rigidly connected together to support the mold box and table D in the following manner.

As can best be seen in Figures 2, 3, and 6 the table 25 is formed along its two sides with a pair of upstanding flange members 33 and 34 which extend throughout the length of the same and are integrally formed therewith. Table 25 is provided with a number of bosses 35 positioned near the ends thereof which bosses are adapted to

receive a number of cap screws 36 screwable therethrough and arranged to project a short distance above the level of the said table. Upon the upper projecting ends of the cap screws 36 are positioned two bars 37 which extend transversely across the table and which have socketed holes 38 formed in the underside thereof in which said bars are seated and held in position upon the cap screws 36. Pallet board B, previously referred to, may be made of wood having a flat top with a pair of battens 40 positioned below the same for use in holding top 39 together and for positioning the same away from the surface on which they rest during curing, to permit of circulation of air around the block. This pallet board B is adapted to rest on the bars 37 which lie adjacent the two battens 40. The table 25 is formed with two openings 41 and 42 extending through the same through which the two said battens are adapted to project. As will be noted in Figure 6 these holes or openings 41 and 42 are made of such a size as to accommodate battens of varying thickness, said openings extending completely across the table to the flange members 33 and 34 so that if desired the battens may be made the full width of the top 39. In positioning the pallet board B within the device 25 the battens are so attached to the top 39 that the same come close to the bars 37. The width of the top 39 is further made such that it just fits in between the two flanges 33 and 34 as clearly shown in Figure 3. It can hence be clearly comprehended that the pallet board B can be conveniently dropped in place upon its support within the machine the same being automatically guided by the flanges 33 and 34 and the bars 37 into its proper position to receive the block after the same has been cast.

The mold C which casts the exterior walls of my improved block comprises four plates or walls 43, 44, 45, and 46 which are all adapted to be hinged to the machine proper below the lower edges thereof and which may swing completely away from the block as shown in Figure 3 or may be raised upwardly and connected together to form a mold for the block as clearly shown in Figures 2 and 5. For hingedly connecting front and rear walls 43 and 45 to the machine proper I form the two flanges 33 and 34 of table 25 with four depending lugs 47 and 48 which extend below the lowermost edge of said table. Pairs of depending arms 49 and 50 are formed on the front and rear walls 43 and 45 of the mold C which extend downwardly from them and are positioned adjacent the lugs 47 and 48 on the flange members 33 and 34. Both the arms 49 and 50 and the lugs 47 and 48 are drilled to receive a pair of pins 51 and 52 which may extend completely across two sets of these

lugs and arms to form a hinged connection for the front and rear walls of the mold. It can readily be seen that when these walls are swung outwardly the side walls may 5 take the positions shown in Figure 3 being free from the block and the pallet board B. In a similar manner the end walls 44 and 46 of the mold proper are provided with hook shaped depending arms 53 and 10 54 which also extend below the lower-most edges of the same and which are adapted to enter into a number of slots 55 formed in the head portions 24 of standards 20 and 21 adjacent the end walls of the legs 22 and 23 at 56. These end walls and the arms 15 53 and 54 are similarly drilled to receive pins 57 and 58 which extend completely through both of the end walls 56 on each of the standards 21 and 22 and the corresponding arms 54 and 53 to hingedly connect said end walls to said standards. As 20 will be noted in Figure 2 the positioning of the hooked arms 53 and 54 is such that a pallet board of greater length than 25 that required for the machine may be inserted within the machine without engaging the said arms thereby permitting free operation of the machine and at the same time permitting a certain amount of irregularity of construction of the pallet boards. 30

The action of the sides and ends of my improved mold when the same are swung downwardly is such that the said walls are separated from the block proper without 35 causing the corners or the surface of said block to adhere thereto. I have made a number of experiments with the positioning of the hinges of these walls and have found that when the hinges are positioned near 40 the corners of the said walls that the surface of the block or corners or other portions of the same adhere to the walls of the mold when the same are swung outwardly thereby defacing the block. With the hinge 45 positioned a substantial distance below the lowermost corners of the said walls this defect is entirely eliminated permitting of rapid removal of the mold proper from the block. 50

As can be clearly comprehended my machine is adapted to form a number of different kinds of blocks by merely interchanging and varying the assortment of core members and face plates provided with the machine. The machine is, however, particularly adapted to cast blocks having a continuous air space extending through the same, the parts for which will now be described in detail. 55

Attached to the two end walls 44 and 46 of the mold box C I provide a pair of V-shaped hollow castings 59 and 60 best shown in Figures 5, 6, and 7 which are bolted thereto by means of two bolts 61 and 62. These 60 castings are removably attached to the end 65

plates 44 and 46 by means of said bolts and at any time may be removed and replaced by other core members if desired. Castings 59 and 60 are formed with converging side walls 63 and with an upper wall 64 and a back 65 through which the aforementioned bolts 61 and 62 pass. When the mold is assembled the castings 59 and 60 take the position shown in Figure 5 the lower edges 66 thereof being positioned on top of the pallet board B as clearly shown in Figure 6. By means of the adjusting screw 36 the head of the pallet board B may be raised so that the upper surface thereof comes in contact with the edges 66 of the castings 70 75 59 and 60 so that leakage in material beneath the same is prevented. In this manner any thickness of pallet board B may be used and if desired either a steel, cast wire or wood pallet board may be employed the same being properly adjusted until the upper surface thereof comes in contact with edges 66 of said castings. As can be seen in Figure 5 castings 59 and 60 form the 80 end portions of the core which provides the continual air space extending through the block. The intermediate portion of the core is formed by a casting indicated at 67 in Figure 5. This casting is formed with side walls 68 and a top 69 integrally connected therewith, which top 69 lies flush with the top 64 of the casting 59 and 60 when the same is positioned within the mold. The side walls 68 are made to form a core of greater width across the center of the same as indicated at 70 and the said walls are made so that the same taper from the top to the bottom of the device. In conjunction with the side walls 68 of this casting the same is formed with two guides 71 and 72 positioned in a vertical position at the ends of the same thus completely enclosing the said casting excepting at the bottom thereof. By means of the guides 71 and 72 the casting 67 may be slidably positioned between 70 the castings 59 and 60. The edges of the said guides 71 and 72 being slidable between the forward edges 73 of the wall 63 of said castings, these guides extend outwardly through the tops 64 of said castings through a pair of notches 74 formed at the converging end thereof. With this construction it can clearly be comprehended that the casting 67 which forms the central portion of the core of the mold C can be easily raised and lowered relative to the castings 59 and 60 attached to walls 44 and 46 of the said mold. For handling casting 67 I provide a U-shaped handle 75 adapted to normally lie flush with the upper surface 69 of said casting in a recess 76 formed within the same, said handle being provided with a pair of nuts 77 and 78 attached to the lower end of the same so that when the said handle is raised said nuts engage the lower sur- 85 90 95 100 105 110 115 120 125 130

face of the top 69 causing this section of the core to be raised therewith. It can hence be comprehended that casting 67 can be quickly and easily inserted into or removed from the device.

The operation of the device is very simple. The walls 44 and 46 with castings 59 and 60 attached thereto are swung upwardly together with the walls 45 and 53 which are locked in position by a device which will be later described. This brings casting 57 and 60 into position shown in Figure 6. With the parts so arranged casting 67 may be dropped into place between castings 59 and 60, the guide-ways 71 and 72 being operated between edges 73 of wall 63 of said castings 59 and 60, said guideways passing through notches 74 therein. When the casting 67 is properly positioned the same forms a continuous core together with castings 59 and 60 which extends completely across the mold box C to divide the same into two distinct compartments, one on each side of the mold. After the parts have been so arranged concrete in a semi-moistened state may be poured into the two compartments and rammed in place, after which the upper surface of the same may be troweled smooth to the level of the core members 59, 60, and 67 and the tops of the walls 43, 44, 45 and 46. At this stage the central core member 67 may be removed by grasping the handle 75 and drawing the entire core member directly upward from the mold proper and completely removing the same from the machine. After unlocking the device the end walls 44 and 46 may be swung outwardly by means of two handles 79 and 80 connected therewith to take the positions shown in Figure 4. Upon the swinging outwardly of these walls, core members 59 and 60 follow therewith, due to the convergence of the sides thereof cause the said core members to withdraw from the mold making a clean surface on the block proper. After these two walls have been swung outwardly walls 43 and 45 may be correspondingly swung outwardly thereby completely removing the said cores and walls from the block letting the block stand in an isolated and freed position upon the pallet board B as clearly shown in Figure 3. In order to remove the block from the machine it is merely necessary to grasp the pallet board B at its two ends and lift the same upward from the machine with the newly formed block positioned thereon and deposit the same at any locality desired. For readily permitting access to the ends of the pallet board B the table 25 has been formed with the flange members 34 and 33 extending around the same on two sides only, thereby leaving openings 81 and 82 in the ends of the device through which openings the fingers may be inserted to engage the under-

side of said pallet board B. In this manner the board can be easily and conveniently removed as soon as the block has been formed.

For locking the sides of the mold box C in place I provide a locking bar shown in detail in Figures 8 and 9. This bar, as indicated in its entirety at 83, comprises a central portion 84 having two off-set end portions 85 and 86. The end portions 85 and 86 are each provided with a notch 87 extending into the same. This notch is adapted to cooperate with a similar notch 88 formed in a lug 89 extending outwardly beyond and connected to the two side walls 43 and 45 of the mold C. As can clearly be seen in Figure 5 the edges of the side members 43 and 45 are formed rabbeted at 89 to form a seat for the edges of the end members 44 and 46. When the various sides and ends of the mold are swung inwardly the said walls are held in proper relation by these rabbeted edges so that a square and perfect formed block is secured in every instance. The locking bar 83 is applied by simply placing the same with the notches 87 co-acting with the notches 88 on lugs 89. This serves to hold the parts in place. The two side walls 43 and 45 being held from outward movement by the said locking bar and from inward movement by direct engagement with the edges of the end walls 44 and 46. In a similar manner the end walls 44 and 46 are held from inward movement by means of the shoulder 89 and from outward movement by direct engagement with the said locking bar 83. For unlocking the device it is merely necessary to grasp locking bar 83 by its central portion 84 which is positioned a distance away from the end walls 44 and 46 to permit of conveniently grasping the same, and to raise said locking bar from its seat within the notches 88 on the lugs 89 and to completely remove the same from the device. After this has been accomplished the various parts of the mold may be removed and swung outward to completely free the block as before mentioned.

As before described and as can be clearly seen in Figure 3 each of the blocks formed comprises a pair of sections 90 and 91 which are spaced from each other and formed separately therefrom. These sections are held together by means of a number of steel rod anchors 92 formed with angular bent ends 93 which serve to hold the same within the block and thereby rigidly connecting the two sections 90 and 91 of the block together so that from a structural point of view the block is as substantial as if each of the two sections of the same were cast with integral connecting webs. In this manner a block is formed which has continuous air space extending through the same and which still has all

the requirements for strength and rigidity necessary to the proper use of the block.

The device for holding the anchors 92 within the block and for permitting of the removal of the core members from the same is shown in detail in Figure 7. A pair of notches 94 and 95 are provided in each of the edges 73 of the walls 63 of both of the castings 59 and 60. These notches are formed with flaring sides which have an arcuate portion whose center is that of the point of pivot at 97 of the arms 53 or 54 as the case may be. At the apex of the notches 94 and 95 the same formed with a circular recess 98 adapted to receive the anchors 92 as clearly indicated in Figure 7. These recesses are so positioned that when the casting 67 is in place the said anchors 92 lie adjacent the end of the guide-ways 71 and 72 as shown in section in Figure 6, and in dotted lines in Figure 5. With the edges 96 of slots 94 and 95 formed arcuate it can be readily understood that if either of the entire end walls with castings 59 and 60 mounted thereon are moved outwardly on their points of pivot that the said anchors 92 and 93 are permitted to remain within the block while the said wall 63 of said castings move away from the same to free said anchors. For momentarily holding anchors 92 within the recesses 98 I provide a spring clip 99 which has its ends 100 and 101 formed to engage the said anchors 92 to hold the same in place but to permit of the same being drawn outwardly along the surface 96 of slots 94 and 95 to permit of the removal of said anchors from the core members 59 and 60. The spring clip 99 is mounted in a wood block 102 which is driven in between the walls 63 of castings 59 and 60 through an opening 103 in the end wall 65 thereof. Clip 99 extends completely through the block and may be secured thereto by means of a nail or screw 104 driven into the same. When castings 59 and 60 are bolted to the face plates 46 and 44 block 102 is securely held in place and spring member 99 positioned as shown in the drawings. To apply one of the anchors to the device spring member 99 is grasped by one of its extreme ends which is normally positioned as shown in Figure 7 and the same drawn towards the center of the casting. This draws the said spring 55 away from opening 94 which permits the insertion of the anchor rod therein. Upon releasing the spring the same engages the rod as clearly indicated in connection with the spring member 101 in said figure. 60 When the mold is removed the pressure of the spring 99 upon either of the anchors 92 is so slight that the same is distorted and the core removed without displacing or disturbing the position of the said anchors 65 within the block proper.

It can be clearly understood that with my invention the entire block may be rammed and formed and the core and mold members removed without inverting or disturbing the block after the same has been positioned upon the pallet. After this the entire pallet and block may be carefully removed and the block set aside to cure so that the exact shape of the block as formed in the mold is maintained and at the same time the structure of the concrete is not disturbed to cause the same in any way to disintegrate or lose its strength. With the anchors as formed the two sections of the block are firmly held together and the block has all the characteristics of a building block formed with integral web members while at the same time the block has all of the advantages of a continuous air space.

For supporting the tools used in connection with the ramming and casting of the block together with the supporting of the core members within the mold I employ the table D previously referred to. This table comprises a top 105 which is supported on two cast brackets 106 which are provided with flanges 107 by means of which the same may be bolted to the standards 20 and 21 by means of bolts 108. Brackets 106 extend upwardly and toward the rear of the machine so that when the top 105 is mounted on the same said top comes substantially flush with the top of the mold box C and is positioned to the rear of the machine a distance sufficient to permit of swinging rearwardly the mold wall 45 to permit the removal of the blocks from the machine. In this manner the operation of the device is not hindered in any way and a place for all the tools is provided which is handy and convenient.

Although I have so far described my machine as forming a block with a continuous air passage the machine may be adapted to form a number of other blocks. In conjunction with the block having the straight continual air space I also provide a mold for a corner block which is clearly shown in Figure 10. In this form of the invention castings 60 and 67 are employed as heretofore, casting 60 being attached to the mold wall 45 and casting 67 being positioned freely within the mold as in the other form of the invention. In addition to this I employ another casting 109 the shape of which is clearly shown in said figure, which casting is provided with a guide 110 corresponding to the guide 71 of casting 67 which guide issues to the side of the core as clearly indicated. A guide way 111 formed as indicated cooperates with the guide 71 so that when the two castings are held together by means not shown in the drawings the same form a continuous core making a right angle.

Guide 110 is formed to cooperate with the guide way 112 which is formed on a casting 113 similar to the casting 59. This casting is somewhat shorter than casting 59 being 5 in all other ways similar therewith and is directly bolted to the face of the mold wall 43 to cooperate with the core members 67 and 107. Anchors 92 are supported in the casting 130 in the same manner as in casting 10 60 or 59 so that when the central core member 67 with the casting 107 attached thereto is removed the walls of the device may be 15 swung outwardly leaving the block intact upon the pallet board, said block being formed with the angular air space extending completely through the same as required.

For forming a half block or a quarter block I provide a number of division plates which are adapted to be positioned transversely or longitudinally of the device. Two 20 such plates are shown in Figures 15 and 12. Plate 114 which is of uniform thickness and which is provided with over-hanging depending lugs 115, issuing from the upper 25 corners thereof beyond the exterior of the mold box proper is shown in Figure 12. These lugs are adapted to become seated in a pair of socketed projections 116 formed on the exterior of the mold walls 44 and 46. 30 When the internal core members of the machine are moved this plate may be inserted in place thereof to form a solid block with half the normal thickness of the ordinary block. In Figure 16 the use of plate 114 is 35 clearly indicated. For removal of plate 114 from the machine I provide a handle 117 issuing upwardly therefrom by means of which said plate may be grasped and inserted into or lifted out from the mold box.

40 The device shown in Figure 12 comprises a plate 118 which is provided with a vertical slot 119 extending completely through the same throughout its entire length. This plate is provided with lugs 115 and a handle 45 117 identical with those shown in Figure 15. Lugs 115 of this plate are adapted to be seated into any pair of a number of socketed 50 projections 120 formed on the upper surfaces of the two mold walls 43 and 45. These 55 sockets are identical with the sockets 116 and serve to support the division plate 118 in either of its quarter position or half position within the mold so that the said plate may be inserted to form a block of quarter, half or three quarters the normal length of 60 the standard sized block. Slot 119 is of such a size as to exactly fit over any of the core members 59, 60 or 67 positioned within the mold box C so that the fragmentary block 65 may be made with the continuous air space to correspond to the regular size block. In Figures 13 and 14 the exact method of applying this device to the invention can clearly be seen.

65 In Figure 11, I have shown my improved

concrete block machine equipped to cast a chimney block. For this purpose I provide a semi-circular casting 121 which is preferably formed hollow and which is adapted to be bolted to the side 45 of the 70 mold box proper by means of a bolt 125 passing directly through both said members, which bolt is formed with a counter-sunk head so that the same lies flush with the exterior surface of said casting. Casting 75 121 is the same height as the wall 45 and casts a continuous semi-circular groove along one side of the block. When two such blocks as are indicated at 123 formed by 80 this machine are placed together they form a continuous circular flue and a rectangular exterior.

The advantages of my invention are manifest. An extremely and simple device is provided in which all the building blocks necessary in building construction can be 85 formed. In addition to this the machine forms a block with a continuous air space making the block particularly desirable for buildings where heat and dryness are required. Inasmuch as the blocks are not disturbed after the same have been cast the blocks always remain intact throughout the curing thus providing a block of substantial 90 construction and suitable strength and integrity. The simplicity with which the device operates makes it possible to turn out a great number of blocks a day thus clearly reducing the cost of making the blocks and at the same time making the machine highly 95 efficient and practical.

In accordance with the patent statutes I have described the principles of operation of my invention, together with the apparatus which I now consider to represent the 100 best embodiment thereof, but I desire to have it understood that the construction shown is only illustrative and that the invention can be carried out by other means and applied to uses other than those above 105 set forth within the scope of the following 110 claims.

I claim:

1. A concrete block machine comprising a pair of supporting standards having flanged legs, a table secured to said legs, a pair of flanges extending along said table, a mold comprising side and end walls positioned above said table, a pair of lugs formed on each of said table flanges, a pair of arms formed on each of said mold sides and pivoted to said lugs, slots formed in said legs adjacent the flanges thereof, and depending arms formed on said mold ends extending downwardly into said slots and along said leg flanges and means for pivoting said arms to said leg flanges.
2. A concrete block machine comprising a mold having a support, side and end walls hingedly connected to said support, core 130

members mounted in said end walls, and a notch formed in the inner edge of said end core members having an edge formed concentric with the point of pivot of said end 5 wall and an anchor rod adapted to be positioned within said notch and to remain within the mold when the core member is removed, said anchor moving along the arcuate surface of said notch to become freed 10 therefrom.

3. A concrete block machine comprising a supporting standard, a table mounted on said support, a pair of longitudinal flanges extending along the front and back of said 15 table, a pair of supporting members positioned within said table between said flanges, a pallet board having a pair of battens adapted to be positioned adjacent said supports, said pallet board being of a width 20 equal to the distance between said flanges, and openings formed in the ends of said table to permit of the insertion of the fingers between the pallet board and said table for the removal of the same from the machine.

25 4. A concrete block machine comprising a supporting standard, a table mounted thereon, a pair of flanges formed on the front and back of said table, pairs of cap screws screwable through said table and projecting 30 above the same, a pair of cross bars mounted on said pairs of cap screws and movable therewith, a pallet board adapted to be positioned between the flanges and resting on

said movable bars and means on said pallet board positioned between said bars for holding the same from movement within the machine. 35

5. A concrete block machine comprising a base member forming a support adapted to receive a pallet board, side and end walls 40 mounted upon said pallet board, arms formed on said side and end walls and extending downwardly below said pallet board and being pivoted to said base for permitting said side and end walls to swing outwardly and downwardly, a central core member positioned upon said pallet board and V-shaped core members cooperating with said central core member secured to said end walls adapted to swing outwardly 45 therewith to free said core members from the mold. 50

6. A concrete block machine comprising a mold having a support, side and end walls pivoted thereto, core members mounted on 55 said end walls, said core members having a pair of notches adapted to receive anchor rods, a spring clip positioned within each of said core members attached to said end walls having its ends projecting outwardly 60 adjacent said notches and adapted to engage the anchor rods positioned therein and to yieldingly hold the same in place.

In testimony whereof I affix my signature.

FREDERICK E. KINSMILLER.
